UNITED STATES PATENT OFFICE.

MAXIMILIAN CHARLES SCHWEINERT, OF NEW YORK, N. Y.

QUICK-ACTING PUMP COUPLING.

Application filed October 9, 1920. Serial No. 415,884.

To all whom it may concern:

Be it known that I, MAXIMILIAN CHARLES SCHWEINERT, a citizen of the United States of America, residing in the borough of 5 Manhattan, city, county, and State of New York, have invented certain new and useful Improvements in Quick-Acting Pump Couplings, of which the following is a specification.

10 This invention relates to pump coupling or the like and aims to provide certain improvements therein.

The invention is particularly directed to that type of coupling which has a mutilated thread which is adapted to be slipped over the end of the valve casing in a position wherein the coupling is displaced from its final position to a sufficient extent to enable the threads of the valve casing to pass 20 the threads on the coupling. It has heretofore been proposed to provide a coupling of this type in which the coupling is canted or tilted with relation to the valve casing until it assumes approximately its innermost position whereupon it is straightened in line with the valve casing and the threads thus engaged. In such types of couplings there have been no means provided for holding the coupling in its finally adjusted or 30 working position. Consequently it is liable to cant back into its removable position particularly before pressure is applied. When the pressure of air is upon the coupling, such disengagement is less likely since pressure tends to hold the device in its engaged position.

According to the present invention I provide a positive means for holding the coupling in such position irrespective of conditions of pressure. To this end I provide 40 a coupling having a mutilated thread so constructed as to be applied to the valve casing with the mutilated thread in engagement therewith, and a movable member preferably of rotary construction which holds the parts so that escape of the coupling thread and valve thread is impossible without manual adjustment.

Referring to the drawings which illustrate several forms of the invention,—

Figure 1 is an elevation of one form of coupling as applied to a valve casing;

Fig. 2 is a diametrical section of the coupling removed, and on an enlarged scale;

55 Fig. 3 is a bottom view of the coupling;

Fig. 4 is a bottom view of the coupling with the manipulating member removed;

Fig. 5 is a diametrical section of the coupling nut;

Fig. 6 is an elevation of the actuating 60 sleeve;

Fig. 7 is a bottom view of the same;

Fig. 8 is a diametrical section of a modified construction;

Fig. 9 is a bottom view of a modifica- 65 tion;

Fig. 10 is a similar view showing the parts in different relative positions.

Referring to the drawings, A indicates the coupling as a whole, which, as shown in 70 Fig. 1, is applied to the valve casing B.

The coupling A comprises a body portion C having an internal bore D which contains a packing E preferably of the piston type. F is a nut having a mutilated thread G 75 which preferably is formed separately from the body of the coupling, the mutilated thread being on one side of the nut and adapted to engage the nipple on the valve casing, as is best shown in Fig. 8. 80

In the type of coupling shown in Figs. 1 to 7, the nut has a cut-away portion H into which the valve nipple may be introduced when in canted position, and upon straightening the mutilated thread G is 85 brought into engagement with the thread of the valve casing.

According to the present invention I provide means for holding the parts in engaged position, such means being preferably adjustable by hand and preferably comprising a rotary member I which in the construction shown as a flange J for swiveling it to the body of the coupling. The holding member I has a bottom flange K which is recessed at 90 L so that when the member is in position of Fig. 2 it does not interfere with the application of the coupling to the valve. On the other hand when the member is turned half circle the edge of the recess L engages the 100 opposite side of the valve nipple and prevents disengagement.

A pin such as M is best arranged on the nut so that it forms a stop for the holding member in either of its adjusted positions. 105

In the construction shown in Figs. 8, 9 and 10, instead of the cut-away portion H the coupling is provided with an enlarged bore on one side, indicated at O. This permits the coupling to be applied to the valve 110

nipple without canting it, the nipple passing into the coupling in a substantially axial position. The holding member I' in this construction acts also to cam the coupling side-wise so as to throw the valve nipple into engagement with the mutilated thread G'. The construction of holding member for this purpose is best illustrated in Figs. 9 and 10. The flange K' has a camming corner or surface P which engages the valve nipple, as the holding member is turned and moves the coupling laterally until the thread is engaged. Fig. 10 shows the valve nipple when first inserted and lying over to the left with the threads disengaged. Fig. 9 shows the position of the parts after the holding member has been turned to cam the coupling to the left, thus bringing the nipple into engagement with the mutilated thread G'.

20 The device is preferably provided with some construction of packing washer which will make a tight joint with the coupling under pressure. The packing E is of this type. Preferably the wall of the coupling is cut away at Q so as to admit pressure to the back of the packing and the packing is moved downwardly under the pressure against the end of the valve nipple, as indicated, for instance, in Fig. 8.

30 While I have shown and described several forms of the invention, it will be understood that I do not wish to be limited thereto since various changes may be made therein without departing from the spirit of the invention.

35 What I claim is:—

1. A pump coupling or the like, having an imperforate bore adapted to receive the end of a valve casing, a part of the coupling having a mutilated thread and a part of the coupling having means to hold the valve casing in engagement with said thread, and one of said parts being movable about the

axis of the body portion with relation to the other whereby in one position the valve may be inserted and removed without resorting to a threading or unthreading operation, and in another position the coupling may be locked in engagement with the valve.

2. A pump coupling or the like, having a 50 mutilated thread and an enlarged opening adapted to permit the entrance of a valve, and the pump coupling adapted by a lateral movement to engage the thread of the coupling with the thread of the valve, and a 55 rotary means movable about the axis of the coupling and adapted to bear against the valve to prevent the disengagement of said threads.

3. A pump coupling or the like, having a 60 mutilated thread and an enlarged opening adapted to permit the entrance of a valve, and the pump coupling adapted by a lateral movement to engage the thread of the coupling with the thread of the valve, and a 65 rotary means adapted to bear against the valve to prevent the disengagement of said threads, said means comprising a collar swivelled to the coupling, said collar adapted in one position to permit insertion of the 70 valve and in another position to prevent its withdrawal.

4. A pump coupling or the like, having a bore provided with a mutilated thread, the opposite side of said bore being bevelled to 75 permit the entrance of a valve casing when tilted with relation to the coupling, and means for holding the coupling with its threads engaging those of the valve casing, and said means comprising a collar swivelled 80 to the coupling and adapted to bear against the side of the valve casing.

In witness whereof, I have hereunto signed my name.

MARXIMILIAN CHARLES SCHWEINERT.
